(Cl. 179—9)

The present invention relates to telephone systems with main and subsidiary exchanges and automatic operation. The general object is directed to improving these systems by making them more dependable and efficient by avoiding the disturbances which occur especially during the setting up of calls and during metering, by means of auxiliary devices of the simplest possible form.

According to the invention the metering operation occurring at the end of a call is prevented from being disturbed by the premature release of the call, in that a relay located in the main exchange and associated with the connecting line between the main and subsidiary exchange, and which maintains the outgoing connections of the subscribers of the subsidiary exchange, is held energized during the metering operation which takes place after the clearing signal has been given.

Since the meters provided for metering the outgoing calls of the subsidiary exchange subscribers are centralized in the main exchange, it is convenient also to influence these same meters in the case of internal calls, in order to avoid the necessity of additional metering devices. This is achieved according to the invention in that, in the case of internal calls between subscribers of the same subsidiary exchange, and from among the meters centralized in the main exchange belonging to subscribers connected to the subsidiary exchange, the meter of the calling station is connected up by switching means in the main exchange characterizing the calling subscriber.

Besides the special formation of the switching devices of the main exchange, the construction of the subsidiary exchange devices for making the systems with main and subsidiary exchanges more dependable and efficient is of particular importance. Thus, for example, the necessary disconnection of the other subscribers' lines from a common calling circuit has previously been effected by relays common to several subscribers' lines. Since for the satisfactory working of the system the common relays can only be provided with a definite number of contacts the arrangement of several common relays is always necessary in those cases when the number of subscribers' lines exceeds a definite number. According to the invention the number of these common relays is reduced in that in the normal condition of the selectors of the subsidiary exchange the subscriber's lines attached to these are connected to the calling circuit passing to the main exchange partly over contacts controlled by the selectors of the subsidiary exchange, and partly over the contacts of relays common to several subscribers.

Three separate embodiments of the invention are illustrated in Figs. 1, 2, and 3.

In Fig. 1 a subsidiary exchange UA without batteries is shown as an embodiment of the invention, which has access to a main exchange HA over the connecting line consisting of two leads. The connection of the subsidiary exchange subscribers to this connecting line takes place over a selector DB10 which for outgoing calls acts as a call finder, and for incoming calls is set by numerical impulses as a final selector. In the normal condition of the system relay L10, and further relays (L11, L12) in case the contacts to be provided for each subscriber cannot be operated by one relay, is operated over one lead of the connecting line. These relays connect all the subscribers of the subsidiary exchange in common to the calling circuit through their working contacts and on deenergizing which occurs when a subscriber calls, cause a switching over of the calling circuit so that the individual subscribers can be tested. In order to reduce the number of relays of this kind to a minimum, contacts operated mechanically by the selector of the subsidiary exchange are used for this purpose, for example 1w10 (1—17) and which are opened on the first switching motion of selector DB10 and remain open until position 17.

The setting of selector DB10 in the subsidiary exchange UA always takes place under the control of the main exchange HA, both in the case of outgoing calls, when the selector is acting as a call finder, and also in the case of incoming calls when the selector is acting as a final selector.

As already mentioned, in the normal condition of the system relay L10, and, if present, also relays L11 and L12 are energized, over the circuit: earth, relays L12, L11, L10, wiper a in position O, winding I of relay U10, lead a of the connecting line, contacts 27c10, 39an10, wiper dIV10 in position O, contact 43x10, winding I of relay X10, battery, earth. In this circuit only relays L10, L11 and L12 are energized, while relay X10 does not receive sufficient current.

Outgoing traffic

When subscriber A1 of the subsidiary exchange takes up his receiver the following circuit is set up: earth, contact 20u10, winding II of relay U10, wiper b in position O, lead b1, subscriber A1, lead a1, contact 1w10 (1—17), wiper a in position O, winding I of relay U10, lead a, contacts 27c10, 39an10, wiper dIV10 in position O, contact 43x10, winding I of relay X10, battery, earth. Besides the transitory energizing of relay U10 relay X10 also energizes in this circuit and locks up by the closing of contact 42x10 in series with its winding II. The circuit just described passing

60

over the α lead is opened at contact 43x10. In the subsidiary exchange relays L10, L11 and L12 release so that the switching magnet W10 of the selector in the subsidiary station is connected to the b lead over contact 23 I 10. The following circuit is thus set up through the main exchange: earth, contact 23 I 10, switching magnet W10, contact 22u10, lead b , contacts 24c10, 48y10, relay K10, battery, earth. In this circuit both the switching magnet W10 in the subsidiary exchange and also relay K10 in the main exchange are energized so that the switching device in the subsidiary exchange is advanced one step. Contact 52k10 switches on the switching magnet D10 in the main exchange through contact 53h10, so that the wipers d I 10—d IV 10 operated by this switching magnet D10 also advances one step. Through contact 57d10, which is operated each time switching magnet D10 energizes, relay Y10 is energized over: earth, contact 57d10, resistance Wi4, winding I of relay Y10, battery, earth. Thereupon the energizing circuit of switching magnet W10 and relay K10, completed over the b -lead of the connecting line, is broken at contact 48y10. Switching magnet D10 is likewise disconnected by the opening of contact 52k10. The interaction would if necessary be repeated again and accordingly both the switching device DB10 in the subsidiary exchange and also the switching device in the main exchange would be advanced in step. Since, however, the subscriber A1 of the subsidiary exchange, connected to the first contact is calling, the testing relay P10, which after the occurrence of each step is connected to the α -lead over contact 45y10, is energized in the main exchange after the first step. This testing circuit is completed through: earth, contact 20u10, winding II of relay U10, wiper b in position I, lead b1, subscriber A1, lead a1, wiper a in position I, winding I of relay U10, lead a of the connecting line, contacts 27c10, 39an10, wiper dIV10 in positions I—II, contacts 44x10, 45y10, relay P10, battery, earth. In the same circuit relay U10 is energized in the subsidiary exchange. By the closing of contact 58p10, relay Y10 is next maintained energized over its winding I, while by the opening of contact 22u10, the switching magnet W10 of the switching device in the subsidiary exchange is cut off. The earth previously connected over contact 20u10 is replaced by earth connected over contacts 24c10, 47y10, 46k10 and choke coil Dr11, by the opening of contact 28u10 and the closing of contact 21u10, so that complete symmetry exists between the two speaking leads, and no unbalance occurs in the subsidiary exchange. By the closing of contact 31p10 a loop is also closed for seizing the exchange connecting devices, so that for example a preselector can be set in operation after whose setting relay Cor is energized. The subscriber receives a dialling signal. He can then commence dialling.

On operating the dial the relay P10 in the main exchange used for testing while the selector is being set releases intermittently according to the impulses, while relay U10 in the subsidiary exchange remains energized on account of its construction as a slow acting relay. Relay Y10 similarly holds up in the main exchange during the impulse emission. Contact 31p10 transmits the impulses to the connecting devices of the main exchange by interrupting the line loop. On the first release of relay P10 relay V10 is influenced since contact 51x10 is also closed. The latter relay ensures a clean transmission of the im-

pulses by short circuiting the choke coil Dr10 at contact 30v10 during the emission of the impulses, and disconnecting the condensers (contacts 28v10 and 29v10).

The connecting devices of the main exchange are set in the desired direction by the various impulse trains in any suitable manner, with which we are not concerned, and the desired subscriber is then rung in the known way.

It should be noted that the meters of the subsidiary exchange subscribers are centralized in the main exchange. In order now to be able to influence the corresponding meter when a subscriber sets up a call the meter is connected over a wiper of the switching device in the main exchange which controls the setting of the selector in the subsidiary exchange and is thus advanced in step with the latter. When the conversation has finished a meter impulse is transmitted over the lead c, in any way, with which we are not concerned, which influences the meter SM1 allocated to the calling subscriber. A second winding of relay Y10 lies in the meter circuit and on energizing maintains the connection existing between the main exchange and the subsidiary exchange so that even when the calling subscriber replaces his receiver no release of the selector DB10 in the subsidiary exchange or of the switching device in the main exchange can take place during the metering process. If at the moment that the selector of the subsidiary exchange is engaging a subscriber's line during the further switching after the termination of the conversation, the subscriber of the line in question takes up his receiver, the connecting line leading to the main exchange can immediately be seized again. Since the selector of the subsidiary exchange has advanced in step with the switching device in the exchange, in this case also the meter corresponding to the subscriber reached is again connected to the c-lead.

If a new call does not take place, both switching devices are advanced to position II through the alternating play of the above mentioned relay. In the main exchange relay H10 energizes in this switching position over contact 38y10, wiper d III 10 and resistance Wi7, and by opening contact 53h10 prevents the switching magnet D10 from being operated again and the consequent further switching of the corresponding wiper. The switching magnet W10 in the subsidiary exchange is further operated, however, by the alternate play between relays K10 and Y10, since the corresponding selector has to carry out 17 steps to reach the zero position. This is continued until the selector DB10 in the subsidiary exchange reaches position I7. In this position relays L10, and L11 and L12, now energize over: earth, relays L12, L11, L10, wiper a in position I7, winding I of relay U10, lead a of the connecting line, contacts 27c10, 39an10, 40h10, resistance Wi5, battery, earth. Relay L10 cuts off the operating circuit of switching magnet W10, at contact 23z10, so that relays K10 and Y10 in the main exchange can also no longer energize. By the opening of contact 38y10 relay H10 deenergizes and opens the circuit for the L-relay passing over the α -lead, at contact 40h10. Thereupon this relay again deenergizes. Through the closing of contact 23z10 the operating circuit of switching magnet W10 passing over the b -lead of the connecting line is again closed so that the selector in the subsidiary station makes one switching step (into the normal position). By relay K10 energizing in the operating circuit of switching magnet W10 the switching magnet of the switching device

in the main exchange is now operated over contact $52k10$, so that this switching device also makes one step, likewise into the normal position. Thus both are now standing again in position O. On reaching this position the condition existing when the system is at rest is again set up (L-relay energized).

The number of steps of the selector in the subsidiary exchange are known to be larger than 10 the number of steps of the switching device in the main exchange. Since, however, in order to actually connect up the motor of the calling subscriber through the switching device in the main exchange, the switching device and the 15 selector in the subsidiary exchange must be synchronous, the arrangement is such, as described above, that the motion is synchronous until the 11th contact, i. e. until the first contact without any subscriber's connection, whereupon 20 the selector in the subsidiary exchange travels over the remaining contacts and then accomplishes the last switching step together with the switching device. This release motion is achieved in that up until the 11th contact the 25 relays $K10$, $Y10$ and the magnet $D10$ produce impulses for advancing both switching devices, whereupon the magnet $D10$ is disconnected from the impulse producing circuit and by a switching over process ($H10$) impulses are only produced through relays $K10$ and $Y10$ for the magnet $W10$. In position 17 this then causes a reversal of the change-over device so that for the last switching step the circuit first operative comes into operation again, together with the 35 switching magnet $D10$.

Incoming traffic

The subscribers attached to the subsidiary station can obviously also be called from the main 40 station. The last digit of their call numbers corresponds, for example, to the number of steps which the selector $DB10$ in the subsidiary exchange must take in order to be set on their connections. If they were previously subscribers 45 having individual lines to the main exchange they can retain their original call numbers unaltered. Only the *c*-lead from the final selector has to be disconnected from their previous connections and led to a contact of wiper $d I 10$. The *a*- and *b*-leads of all subscribers' lines incoming from the 50 final selector are connected together in parallel. Thus both subscribers attached to the same level of a final selector and also those attached to different levels of the same final selector or in particular to different final selectors are incorporated 55 in the subsidiary exchange while maintaining their call numbers.

If a final selector (not shown) is set in any manner on the line leading to the subsidiary exchange 60 for the purpose of calling subscriber A5, testing is carried out, in the known way, over the lead $c5$ thus seized, as to whether the line leading to the apartment house exchange is free. If this is not the case, wiper $d III 10$ has left its position O, 65 so that the lead $c5$ incoming from the final selector is open and the calling subscriber receives an engaged signal in the known way.

If on the contrary, the line leading to the subsidiary exchange is free relay $An10$ is energized 70 over the lead $c5$ (lead $c5$, resistance $W19$, contact $36c10$, relay $An10$, wiper $d III 10$ in position O, resistance $W17$, battery, earth). Relay $An10$ lies in a circuit dependent upon wiper $d III 10$, via contact $37an10$. Through the opening of contact 75 $39an10$ the circuit existing for relays $L10$, $L11$ and

$L12$ in the normal condition of the system is broken, so that these relays deenergize. Seizing from the subsidiary exchange is not possible since relay $P10$ which is otherwise used for testing is disconnected and the selector is brought to rest through setting the switching device in the main exchange under the control of the seized testing lead. By the closing of contact $23l10$ after the release of relay $L10$ the operating circuit for the switching magnet passing over the *b*-lead is closed 10 in series with relay $K10$. Both switching devices now move synchronously as was described above for the case of the call of a subscriber of the subsidiary exchange. The advancement now, however, takes place until the wiper $d I 10$ comes to 15 rest on the calling lead $c5$. When this occurs relay $c10$ energizes over the circuit: lead $c5$, wiper, $d I 10$, contact $32an10$, relay $C10$, battery, earth. By the opening of contact $24c10$ the operating 20 circuit of magnet $W10$ and also the control circuit for the magnet $D10$ are broken. The speaking leads are switched through to the final selector by the closing of contacts $25c10$ and $26c10$. The ringing current is transmitted to the desired subscriber from the final selector in any of the known 25 ways, and passes over the *a*-lead of the connecting line of the subscriber's station in the subsidiary exchange and the earth in the subsidiary station connected over contact $20u10$. If the ringing current were connected over the *b*-line, 30 then obviously the *a* and *b*-leads must be interchanged.

When the called subscriber replies the ringing current is disconnected by the completion of the loop in the final selector, and by the energizing 35 of relay $U10$ over the speaking leads contact $21u10$ is closed so that now lead *b* of the connecting line is also switched through to the main exchange. The desired subscriber is now connected to the 40 calling subscriber.

After the termination of the conversation lead $c5$ is cut off from the final selector in any desired way, so that relays $C10$ and $An10$, which had established a locking circuit over contact $35c10$, 45 release. In the subsidiary exchange relay $U10$ is deenergized so that the operating circuit for magnet $W10$ in the subsidiary exchange and for relay $K10$ in the main exchange is again completed over the *b*-lead of the connecting line. By relay $K10$, 50 the magnet $D10$ of the selector in the main exchange is switched on through contact $52k10$. Thus the reciprocal play between the two switching devices, already described, causes the advancement into the normal position in the 55 manner described in the case of the release for an outgoing connection.

Special circuits

If the selector in the subsidiary exchange is 60 displaced from position or by hand, and the two switching devices thus become out of step, relays $L10$, $L11$, $L12$ deenergize since the normal circuit is broken at wiper *a* of the selector. The magnet $W10$ is connected in an operating circuit through 65 the closing of contact $23l10$, the circuit being completed as in the case of a call over relay $K10$ in the main exchange and the lead *b* of the connecting line running between the main exchange and the subsidiary exchange. The magnet $D10$ in the 70 main exchange is switched on by relay $K10$, so that both switching devices are advanced under the control of the impulse circuit in the main exchange. Since in this case both switching devices are not synchronous the possibility of a sub- 75

scriber who hangs up during the advancement into the normal position, causing the connecting line leading to the main exchange to be seized must be prevented, for otherwise the meter of another subscriber would be operated in the main exchange. This is prevented in that through the displacement of the selector in the subsidiary exchange by hand, in contrast to the procedure in a normal call, relay $K10$ is energized in the 10 main exchange, so that the testing relay $P10$ in the main exchange is not connected over contact $44x10$, i. e. this relay cannot test and thus the advancement of the switching device into the normal position cannot be interrupted. For the 15 rest the release motion occurs in the same way as after the normal establishment of a call i. e., advancement in step until the eleventh contact of the switch in the main exchange is reached, then the selector of the subsidiary exchange is controlled alone until position 17, and then the last step to the zero position is accomplished by both switching devices in common. The two switches are thus again in corresponding positions.

The same switching operations take place 20 when the switching device of the main exchange is displaced from the zero position by hand.

In this case the wiper d IV 10 cuts off the a -lead of the connecting line so that relay $X10$ 25 cannot be energized. Seizing during the release motion is thus prevented. By the interruption of the circuit existing in the normal condition relays $L10$, $L11$ and $L12$ again deenergize, whereupon the magnet $W10$ in the subsidiary exchange is again connected in an operating circuit over 30 contact $23 \frac{1}{2} 10$, and is influenced by the reciprocal play of relays $K10$ and $Y10$, partly together with the switching magnet $D10$ in the main exchange, and partly independently, as mentioned above, until the zero position is reached. They 35 can then operate synchronously again when the next call is set up.

Each seizing of the devices in the main exchange can be indicated by a seizure lamp L . If desired, each seizing direction can be indicated 40 specifically, if the contacts $55x10$ for the outgoing seizing and $56an10$ for the incoming seizing are wired separately.

In Fig. 2 a subsidiary exchange UA without batteries is shown as a further embodiment of 45 the invention. Several subscribers are attached to this subsidiary exchange who can reach a connecting line leading to a main exchange HA over a selector $DB20$. The setting of the selector, which for outgoing calls acts as a call finder, and 50 for incoming calls as a final selector, is controlled in each of the two directions by a switching device in the main exchange. In order to reduce the number of relays in the subsidiary exchange as much as possible, auxiliary leads are led off 55 from the speaking leads to the subscriber. Moreover, the connecting line between the main exchange and subsidiary exchange is made of four wires, of which one of the two auxiliary wires serves for extending the calling impulses from 60 the subsidiary exchange to the main exchange, and the other for extending the setting impulses transmitted from the main exchange to the selector of the subsidiary exchange. By this 65 arrangement it is only necessary to provide the magnet $W20$ for the selector $DB20$ serving for connection to the subscribers, without further relays being necessary. These wires of the connecting line carry no current in the normal 70 condition of the system.

Outgoing traffic

When subscriber $A1$ of the subsidiary exchange wishes to make a call he takes up his receiver and operates the earthing key $B-1$ attached to his station. Relay $X20$ in the main exchange is thereby operated over the d -lead of the connecting line (earth, key $B1$, contact $201w20$ 1-17) which is operated mechanically by the switching device $DB20$ so that it is open in positions 1-17, 10 d -lead, relay $X20$, wiper d IV 20 in position O, contact $212h20$, resistance $W11$, battery, earth. Relay $X20$ establishes a locking circuit for itself independent upon wiper d IV 20 by closing contact $215X20$. By closing contact $213x20$ the following circuit is set up: earth, magnet $W20$ of selector $DB20$ in the subsidiary exchange, c -lead of the connecting line, contacts $223y20$, $224c20$, 15 relay $K20$, contact $213x20$, resistance $W11$, battery, earth. In this circuit the magnet $W20$ energizes in series with relay $K20$. The selector $DB20$ in the subsidiary exchange takes a step forward whereupon its mechanically operated contact $201w20$ (1-17) opens and its mechanically operated contact $202w20$ (1-16) closes, so 20 that the transitory depression of the key $B1$ suffices to bring about the calling condition. 25

As already stated relay $K20$ energized together with the magnet $W20$ so that the magnet $D20$ of the switching device in the main exchange is also switched on, over contact $219k20$, and hence the switching device in the main exchange advances one step. By the energizing of magnet $D20$ contact $216d20$ is closed so that relay $Y20$ is energized over this contact and resistance $W11$. By the opening of contact $223y20$ the current 30 is cut off from the magnet $W20$ in the subsidiary exchange and relay $K20$ in the main exchange. Magnet $D20$ is also cut off from its energizing current by the opening of contact $219k20$, so that by the opening of contact $216d20$ relay $Y20$ 35 is again deenergized. Contact $223y20$ is thus again closed so that the switching magnet $W20$ in the subsidiary exchange and the relay $K20$ in the main exchange can be energized again. This alternating play is continued 40 until the selector in the subsidiary exchange has reached the position of the calling subscriber. Since in the present example the subscriber $A1$ attached to the first contact of selector $DB20$ is 45 calling, the advancing terminates after one step, and on reaching this calling subscriber the following circuit is set up: earth, contact $205x20$, winding II of relay $Y20$, contact $206cor$, a -lead of the connecting line, wiper a of the selector in the subsidiary exchange in position 1, subscriber $A1$, wiper b of the selector in the subsidiary exchange in position 1, b -lead, contact $207cor$, relay Lr , battery, earth. Relays $Y20$ 50 and Lr are energized in this circuit so that a further advancement of the switching device is 55 prevented by the opening of contact $223y20$. Relay $Y20$ for producing the impulses for the selector of the subsidiary exchange and for the switching device in the main exchange thus serves also as a testing relay when setting up 60 outgoing calls. Relay Lr seizes connecting devices in the main exchange in any known manner. A pre-selector or a call finder can thus, for example, be set in operation which establishes a connection with a free numerical impulse receiver in the exchange. When such a 65 numerical impulse receiver is reached relay Cor in the main exchange is switched on over the c -lead. Relay $Y20$ which maintains the connection with the subsidiary exchange is held 70 75

energized through its winding III over the *c*-lead in parallel with relay *Cor* and in series with the meter *SM1* connected over wiper *d II 20*. The meter itself is not yet operated in this circuit.

- 5 By the opening of contacts *206cor* and *207cor* leads *a*- and *b*- are disconnected, so that the subscriber of the subsidiary exchange is switched through as a normal individual line subscriber without any unbalance.
- 10 By sending out impulses which operate on the corresponding numerical impulse receiver in the exchange (not shown), the calling subscriber can set up the desired call.

When the calling subscriber has finished his 15 conversation the call metering takes place. The meters of all the subsidiary exchange subscribers are centralized in the main exchange. The meter corresponding to the calling subscriber is connected through a wiper of the switching device

- 20 *d20* which is set synchronously with the selector in the subsidiary exchange. Metering now takes place in that metering impulses are transmitted to the meter *SM1* of the calling subscriber *A1* which is connected through the switching device, 25 by increasing the strength of the current. Relay *Y20* is held energized in this circuit over its winding III during the metering. Relay *Y20* does not release until, after the metering, the *c*-lead is disconnected. By the closing of contact *223y20* the circuit of relay *K20* and switching magnet *W20* passing over the *c*-lead to the subsidiary exchange is then again closed. The switching device is now advanced into the rest position as in the case of setting on the calling 30 subscriber's line in that the circuit for both switching devices is again made and broken through the alternating play between magnet *W20* and the relays *K20*, *Y20* and the magnet *D20*. Both run synchronously so that when the selector *DB20* comes to a calling subscriber's line both switching devices are immediately brought to rest in the manner already shown, and connecting devices are seized in the main exchange. If no new call has been initiated, relay *H20* is 35 energized in position *II* of the switching device in the main exchange, the circuit being: earth, battery, resistance *W16*, wiper *d III 20* in position *II*, contact *225y20*, relay *H20*, earth. By the opening of contact *218h20* the magnet *D20* 40 is cut off, so that the impulses produced in the main exchange only through relays *K20* and *Y20* now only influence the magnet *W20* in the subsidiary exchange. When the selector in the subsidiary exchange reaches position *II* the mechanically operated contact *202w20* (*i*—*16*) is opened, among others, and thereby relay *K20* is deenergized in the main exchange. Since contacts *213x20* and *212h20* are open a further operation 45 of the magnet *W20* in the subsidiary exchange and of relay *K20* in the main exchange is then prevented. Accordingly, relay *Y20* also releases through the opening of contact *219k30*, whereupon the opening of contact *225y20* relay *H20* is also deenergized. By the closing of contact *212h20* a circuit is again set up through: earth, magnet *W20*, *c*-lead of the connecting line, contacts *223y20*, *224c20*, relay *K20*; wiper *d IV 20* in position *I*—*II*, contact *212h20*, resistance *W11*, battery, earth. The selector in the subsidiary 50 exchange takes a further step which brings it to the normal position whereupon by the closing of contact *219c20* the switching device *D20* in the main exchange is also operated, over contact *218h20*, and by taking one step is brought to the 55 normal position. Thus both switching devices are

brought to the normal position together through the last step.

Incoming traffic

The subscribers who are attached to the subsidiary exchange receive as the last digit of their call numbers the number of the steps which the selector in the subsidiary exchange has to make corresponding to the setting of the final selector in the main exchange. Should they previously have been individual subscribers they can retain their previous call numbers unaltered. Only the *c*-lead of the final selector is disconnected from the previous subscriber's bank positions and is led to a contact of the wiper *d I 20*, which corresponds to the contact of the selector in the subsidiary exchange. The *a*- and *b*-leads of all incoming subscribers' lines are connected in parallel.

If the line leading to the subsidiary exchange 20 is already seized, the wiper *d III 20* is away from the rest position so that the testing final selector finds no potential for testing. The calling subscriber receives the busy signal in the normal way. If on the other hand the line is free then 25 assuming subscriber *A6* is the desired subscriber the final selector tests on lead *c6*, whereupon relay *An20* is energized. Relay *An20* locks up independently of wiper *d III 20* over its contact *226 an20*, while contact *214an20* connects battery to the *c*-lead leading to the subsidiary exchange. Relay *K20* is thus energized in the main exchange and switching magnet *W20* in the subsidiary exchange. The alternating play between the magnet *W20* and relays *K20* and *Y20*, which is 30 operated through the magnet *D20*, and which has already been described in the case of establishing an outgoing call, now sets in, so that both switching devices are rotated synchronously until wiper *dI 20* stands on the incoming lead *c6*. 40 Relay *C20* connected through contact *222an20* now energizes over this lead and at contact *224c20* breaks the operating circuit (lead *c*) for the magnet *W20* and the relay *K20*. Both switching devices are brought to rest. Previously contact *227an20* connected earth to the winding of 45 relay *Cor* so that this relay energized and prevented the connecting line from being seized from the subsidiary exchange, by opening contacts *206cor* and *207cor*. Through the closing of contacts *203c20* and *204c20* the desired subscriber's line is switched through to the final selector. It is now connected to the final selector contact bank just as a normal individual subscriber. The subscriber can now be rung in any 50 known way, after which, when the desired subscriber replies, the speaking connection is established.

On the termination of the conversation lead *c6* is cut off in the final selector, so that relay *C20* releases. Contact *224c20* again closes the operating circuit for the switching magnet *W20* in the subsidiary exchange and relay *K20* in the main exchange, passing over the *c*-lead of the connecting line, so that the selector in the subsidiary exchange and the switching device in the main exchange are both advanced under common control. As has already been described in the case of the release of an outgoing call the selector in the subsidiary exchange is advanced 65 to position *II* synchronously with the switching device in the main exchange and is then advanced, after relay *R20* has energized, to position *II*, while the switching device in the main exchange remains still. The last step i. e. the ad- 70 75

vancement into the normal position is again accomplished synchronously with the switching device of the main exchange. A fresh seizure in either direction can only occur when both switching devices have reached the normal position.

Special circuits

If the selector in the subsidiary exchange is displaced from the normal position by hand, the 10 two switching devices are thus brought out of step, and earth is attached to the *a*-lead of the connecting line leading to the main exchange, by means of contacts 202*w*20 (1—16) whereupon relay X20 is immediately operated as in the case 15 of a call proceeding from a subscriber in the subsidiary exchange. The locking circuit of relay X20 is completed by the closing of contact 215*x*20. By contact 213*x*20 the magnet W20 is held until 20 relay K20 has also switched the wiper of the switching device in the main exchange into position 1, so that they are once more in step. When relay Y20 then energizes over contact 216*d*20, the *c*-lead is then cut off so that the circuit over the *c*-lead is broken. Through this 25 alternating operation the switching devices are returned to the rest position synchronously as in the case of the release motion.

If on the other hand the switching device of the main exchange is brought to the normal position by hand the *c*-lead to the subsidiary exchange is likewise connected up over wiper *d* IV 20, and the magnet W20 in the subsidiary exchange is energized in series with relay K20. In this case also both switching devices are controlled in the manner already described until they reach the normal position. Since, however, in this case, under some circumstances the switching devices are not working synchronously i. e. they have become out of step, because 40 the switching device in the main exchange can be moved on by hand quicker than the switching device in the subsidiary exchange, the possibility of seizing under these conditions must be prevented. This is achieved in that the testing 45 relay Y20 of the connecting line can only draw up over the loop of the calling subscriber when the contact 205*x*20 has been connected to the *a*-lead of the connecting line. Since, however, relay X20 is not energized this is not possible, so 50 that the line of a subscriber of the subsidiary exchange who is calling under these circumstances is prevented from being seized.

Each seizure of the connecting line lights up the seizure lamp L. In series with this lamp the 55 seizure can also be recorded. If desired each seizing device can be recorded separately, in which case contacts 220*x*20 and 221*c*20 are wired separately.

In Fig. 3 a system with a main and subsidiary 60 exchange is illustrated as an additional embodiment of the invention. This in addition to the outgoing and incoming calls enables connections to be set up between subscribers of the same subsidiary exchange. For this purpose, in addition 65 to selector DB30 which serves for setting up outgoing and incoming calls (exchange calls) and thus works as a double purpose selector, a second selector LW30 is provided in the subsidiary exchange which serves to set up internal connections 70 within the subsidiary exchange. This auxiliary selector is connected over an auxiliary line (*a*2 *b*2) between the subsidiary exchange and main exchange to the connecting line leading to the main exchange which is seized by calling 75 subscribers.

In order to differentiate between the different call directions i. e. outgoing exchange calls and internal calls, an additional switching device is provided (magnet D30, wipers *d* I 30—*d* IV 30) in the main exchange which is switched round 5 according to the characterizing number dialled so that either a call is set up over the connecting devices of the main exchange, or the auxiliary selector LW30 in the subsidiary exchange can be set on the desired subscriber's connection. 10 In the present embodiment the characterizing is arranged so that by dialling the digit 1 an outgoing exchange call is characterized, while by dialling the subscriber's number directly i. e. any digit except 1, an internal call and thereupon the 15 subscriber desired in the internal call, is characterized.

The characterizing digit for the outgoing exchange call is not taken up by the connecting devices in the main exchange, but only by the 20 characterizing switching device and the auxiliary selector LW30 is provided in the subsidiary exchange.

In the normal condition of the system all the 25 selectors both in the subsidiary exchange and also the switching devices in the main exchange and in addition all the relays, are uninfluenced.

Outgoing calls

When a subscriber takes up his receiver and 30 momentarily depresses the key, for example B2 in the case of subscriber A2, earth is connected to lead *a*1 of the connecting line leading to the main exchange. In the main exchange relay X30 energizes over the circuit: earth, battery, resistance W19, wiper *d* II 30, winding I of relay X30, contacts 345*x*30, 348*a*30, 350*c*30, lead *a*1, winding I of relay U31, wiper *a*1 of selector DB30 in position O, key B2, earth. Relay X30 locks up over its winding II on closing its contact 375*x*30. 40 Contact 345*x*30 disconnects battery from the lead *a*1 of the connecting line. Contact 337*x*30, however connects battery to the *b*1 lead. The following circuit is then set up: earth, magnet W31, contact 309*u*31, *b*1 lead of the connecting 45 line, contacts 335*c*30, 337*x*31, 339*x*30, 342*y*30, relay K30, battery, earth. In this circuit the magnet W31 energizes in the subsidiary exchange and relay K30 in the main exchange, so that selector DB30 in the subsidiary exchange advances one 50 step. Similarly the switching device influenced by the magnet D30 in the main exchange is advanced one step, after this magnet has been energized over contact 316*k*30. On the energizing of this magnet contact 318*d*30 is closed and 55 thus relay Y30 is switched on over resistance W24. This relay opens its contacts 342*y*30, among others, so that the operating circuit of magnet W31 and relay K30 is broken, so that these are both deenergized. By the opening of 60 contact 316*k*30 magnet D30 is also deenergized which again results in the opening of contact 318*d*30 and hence the deenergizing of relay Y30. Contact 342*y*30 is again closed and thereby the operating circuit for magnet W31 and for relay 65 K30 is set up afresh, so that selector DB30 in the subsidiary exchange and the switching device in the main exchange which is influenced by relay K30, advance a further step.

Since the calling subscriber A2 is connected to 70 the second contact of selector DB30, on reaching this contact, after relay Y30 has operated as before after the completion of the second switching step, the following circuit is set up: earth, battery, relay P30, contacts 347*y*30, 346*x*30. 75

348an30, 350c30, lead a1 of the connecting line, winding I of relay U31, wiper a1 of selector DB30 in position 2, subscriber A2, wiper b1 of the same selector in position 2, winding II of relay U31, 5 contacts 307u31, 306w32 (1-17) (mechanically operated by LW30), earth. It should be noticed that the connection of the testing relay P30 to lead a1 by relay Y30 takes place after each step of the switching device in the main exchange. 10 By the closing of contact 319p30 relay Y30 is held energized so that by the opening of contact 342y30 further transmission of impulses for advancing the switching device is prevented. Earth is connected to lead b1 over contact 340y30 and 15 the choke Dr31, so that after opening contact 301u31 and closing contact 308u31 the following locking circuit is set up for relay U31, energized in the above testing circuit: earth, choke coil Dr31, contacts 341k30, 340y30, wiper d IV 30 20 in position 1-11, contact 335c30, lead b1 of the connecting line, contact 308u31, winding II of relay U31, wiper b1 of selector DB30 in position 2, subscriber A2, wiper a1 of selector DB30 in position 2, winding I of relay U31, lead a1 of the 25 connecting line, contacts 350c30, 348an30, 346x30, 347y30, relay P30, battery, earth. At contact 354p30 a loop is closed for the connecting devices of the main exchange so that, just as in the case of a subscriber having an individual line, a pre-selecting device, for example a call finder, is set in operation. After the setting of such a pre-selecting device, if the calling subscriber is connected to a free connecting device he received 30 a signal from the exchange.

35 Since it is an outgoing call which is being set up in the present case, the subscriber must dial the characterizing digit 1. It should be added that relay J30 was energized over contacts 324x30 and 326p30 and also over wiper d III 30 in position 0, so that contact 354p30 which was closed by the testing relay P30 which operates as the impulse relay during the numerical selection is shunted by contact 355j30. The selection of the characterizing digit 1 is accordingly not 40 transmitted to the connecting devices of the main exchange. On the first impulse i. e. on the first deenergizing of relay P30 the magnet Di30 of the characterizing switching device is operated in the main exchange over contacts 324x30, 327p30, and 328j30, and relay V30 is operated in parallel with the magnet; moreover, by the transitory closing of contact 375p30, battery is connected over contact 374j30 to the b2 lead of the auxiliary connecting line and hence magnet W32 of the auxiliary selector LW30 is operated. 45 By means of relay V30, energized during the impulse emission, the choke coil Dr30 is short circuited by the closing of contact 352v30, and by the opening of contacts 351v30 and 353v30 the condensers in the speaking leads are disconnected so as to insure a more clear impulse emission. 50 After the one impulse has been given relay V30 deenergizes on account of the prolonged opening of contact 327p30, so that relay J30, which after one step has been made holds up over wiper d III 30 in position 1 and over contact 55 325v30, is deenergized. The short circuit of impulse contact 354p30 is accordingly removed by the opening of contact 355j30 so that the next 60 impulse trains can be transmitted to the connecting devices of the main exchange. The magnet W32 in the subsidiary exchange, which previously displaced the auxiliary selector LW30 one step, can no longer be effected since the corresponding impulse is broken at contact 374j30.

When the desired subscriber is reached, after testing on the contact in the normal way, ringing current is transmitted and the speaking connection is established on the desired subscriber replying. When the conversation has finished 5 a metering impulse is transmitted on the c-lead in any desired manner which does not concern us here. This is extended to the meter SM2 in the main exchange corresponding to the calling subscriber of the subsidiary exchange. The connecting of the corresponding meter takes place on the setting of selector DB30 in the subsidiary exchange by the switching device in the main exchange controlling this selector. 10 By the switching on of winding II of relay 15 Y30 in the c-lead, which relay assists in sending out the control impulses, the existing connection is prevented from being released during this metering even when the calling subscriber replaces his receiver and thereby releases relay 20 P30 which lies in the circuit of the speaking current. When the metering is completed and the calling subscriber replaces his receiver relays P30 and U31 deenergize. Since a locking circuit no longer exists for relay Y30 in the c-lead it is 25 disconnected by the opening of contact 319p30 so that it deenergizes. At contacts 342y30 and 309u31 the operating circuit through magnet W31 and relay K30 in series is closed again, so that now, in the same way as for the setting of 30 selector DB30 on the calling subscriber, this is again controlled synchronously by the switching device in the main exchange. If the selector DB30 thus moves on to a subscriber's line in which the subscriber has just taken up the receiver, seizing can at once take place again, since both the selector in the subsidiary exchange and the switching device in the main exchange are both in the same switching position, so that the meter in the main exchange corresponding to the 35 calling subscriber is also connected up when the switches are brought to rest. If such a call does not occur, and selector DB30 and the controlling switching device in the main exchange accordingly reach position 11, relay E30 energizes in 40 the main exchange over: earth, battery, relay E30, wiper d III 30 in position 11, contact 324x30, earth. Relay E30 establishes a locking circuit for itself over its contact 363e30. The operating circuit passing over the b1 lead is broken by 45 contact 339e30, and also battery is connected to lead b2 of the auxiliary connecting line, so that now magnet W32 of selector LW30 which stands in position 1 is influenced in series with relay K30 of the main exchange. The impulse circuit 50 previously operating magnet D30 is correspondingly opened at contact 312e30 and is switched over to magnet D130 of the characterizing selector by the closing of contact 313e30. The auxiliary selector LW30 is accordingly switched on one step, 55 and through the energizing of relay K30 in the same circuit magnet D130 is operated over contact 316k30, and likewise advances the characterizing selector one step. Relay Y30 is operated by the closing of contact 317d30, and by 60 opening contact 342y30 breaks the operating circuit for the magnet W32 and relay K30. Contact 316k30 is accordingly opened, so that by the disconnection of magnet D130 and the associated opening of contact 317d3, relay Y30 is deenergized and the operating circuit for magnet W32 65 and relay Y30 is again closed. This alternating play is repeated until the characterizing switching device has reached position 11. When this occurs relay H30 is operated over wiper d I 30 70 75

- and contact 316y30, and hence contact 314h30 is opened which now breaks the impulse circuit for magnet D30 and connects relay Y30 directly in this impulse circuit. Relay X30 deenergizes 5 on the opening of contact 312h30. The auxiliary selector LW30 is moved on further by means of impulses from the main exchange, but there the characterizing switching device does not move with it. The switching device LW30 continues 10 to be advanced until it reaches position 17. In this position earth is connected to the lead a2 over wiper a2 of the switching device LW30. Thus relay U32 is energized in the following circuit: earth, wiper a2 of switching device LW30 15 in position 17, winding I of relay U32, lead a2 of the connecting line, contact 344h30, resistance Wi19, battery, earth. By the opening of contact 302u32 the switching magnet W32 is disconnected and also the circuit of relay K30 is broken. The 20 current is cut off from relay Y30 by the opening of contact 316k30 so that this relay opens contact 367y30 and deenergizes relay H30. Contact 344h30 is opened and the energizing circuit of relay U32 described above is broken down. Contact 25 302u32 again closes the operating circuit for magnet W32 and relay K32, so that selector LW30 in the subsidiary exchange advances one step and likewise the magnet D30 energized over contact 316k30 advances the characterizing 30 switching device in the main exchange by one step. Accordingly both switching devices accomplish the last step into the normal position together. In the position 0 of wiper d I 30 relay E30 remains energized over contacts 364h39 and 35 365e30 until, since relay Y30 is energized over contact 317d30 through the last switching step, relay H30 is again energized over: earth, wiper d I 30 in position 0, contacts 365e30, 368x30, relay H30, battery, earth. By the opening of contact 40 364h30 the locking circuit for relay E30 is broken and this relay therefore deenergizes. Relay H30 holds up, after the opening of contact 365e30 over contact 377h30. After contact 317d30 has opened relay Y30 again deenergizes. 45 By the closing of contact 339e30 relay K30 is furthermore again connected to the b1 lead of the connecting line and also preparation is made for switching in the magnet D30 of the switching device in the main exchange in the impulse circuit 50 already described, over contact 312e30. Thereupon only magnet W31 is operated in series with relay K30. The latter causes relay Y30 to energize over contact 316k30, so that this opens the energizing circuit of magnet W31 by opening contact 342y30. By the alternate play of these relays 55 the switching magnet is influenced until the selector DB30 reaches position 17. In this position the following circuit is set up: earth, wiper a1 of selector DB30 in position 17, winding I of relay U31, lead a1 of the connecting line, contacts 330c30, 248an30, 345x30, 344h30, resistance Wi19, battery, earth. Relay U31 energizes and by opening contact 309u31 disconnects the magnet W31. Relays K30 and Y30 then also release so 60 that now relay H30 is deenergized by the opening of contact 367y30. Through the closing of contact 314h30 the switching magnet D30 in the main exchange is connected up while the energizing circuit just described for relay U31 is broken down 65 at contact 344h30. The operating circuit for magnet W31 and relay K30 is accordingly closed again at contact 309u31. The selector DB30 is thus advanced one step and moves into the normal position. At the same time magnet D30 70 is also influenced by the closing of contact 75

316h30 so that the switching device in the main exchange similarly make one switching step which takes it into the normal position. Since the wiper d IV 30 of this switching device has now left contact segments 1—11 further advancement of the switching devices is not possible. All the devices both in the subsidiary and also in the main exchange are now again in the normal position.

Incoming traffic

10

If a subscriber of the subsidiary exchange, for example A2 is called from the main exchange, a final selector, which is not shown, is set by the corresponding numerical selection. If the connecting line leading to the subsidiary exchange is already seized the wiper d I 30 is not in the normal position, so that the final selector cannot test over the c-lead (c2) corresponding to the desired subscriber. The wiper d I 30 remains away from the normal position as long as any of the switching devices of the connecting line either in the main exchange or in the subsidiary exchange are displaced from the normal position. Seizing the connecting line over a final selector is only possible when all these switching devices have reached the normal position. In the present case the final selector tests over the lead c2 corresponding to the subscriber A2. The circuit passes over resistance Wi20, contact 358c30, relay An30, wiper d I 30 in position 0, contact 369an30, resistance Wi22, battery, earth. Relay An30 energizes in this circuit and locks up independently of wiper d I 30 over contact 359an30. At contact 348an30 battery is disconnected from the a1 lead of the connecting line, so that no seizure of the connecting line can take place from the subsidiary exchange. At contact 336an30 battery is connected to lead b1 of the connecting line, through relay K30. The following circuit 40 is thus set up: earth, magnet W31, contact 309u31, lead b1 of the connecting line, contacts 335c30, 336an30, 339a30, 342y30, relay K30, battery, earth. By the alternate play between magnet W31 and the magnet D30 in the main 45 exchange operated by relays K30 or Y30 (as described in the case of outgoing traffic), the selector DB30 in the subsidiary exchange is now advanced synchronously with the switching device in the main exchange operated by magnet D30. This advancement is continued until the wiper d I 30 has reached the lead c2 seized by the final selector. At this moment the selector DB30 50 has also reached the second contact, to which subscriber A2 is connected. When this occurs relay C30 tests over contact 361an30 and by opening contact 335c30 prevents both the switching devices mentioned from being further advanced. At contacts 334c30 and 349c30 the speaking leads 55 of the connecting line are switched over to the speaking leads of the final selector. Relay An30 now holds up over contact 357c30. Ringing current can now be sent from the final selector, which is not shown, to the desired subscriber A2 of the subsidiary exchange in the known way. When the desired subscriber replies the ringing current is disconnected in the final selector in any manner with which we are not now concerned. Relay U31 is operated over the subscriber's loop by the feeding current connected in the final selector, so that the b1 lead of the connecting line is switched through at contact 308u31, and magnet W31 is disconnected at contact 309u31. The subscriber A2 is now connected 60

60

65

70

75

76

to the final selector of the main exchange just as a normal subscriber having an individual line.

When the conversation has finished the *c2* lead is disconnected in the final selector, relay 5 *C30* being thus deenergized. Contacts *334c30* and *349c30* open and break the circuit for the feeding current, so that relay *U31* deenergizes. One effect of this is that the operating circuit for magnet *W31* and relay *K30* is closed through 10 the closing of contact *309u31*. Through the alternate play of the corresponding relays the selector *DB30* in the subsidiary exchange is advanced synchronously with the switching device in the main exchange. Thus, in the same 15 way as was explained in the case of outgoing traffic, the selector in the subsidiary station is first advanced synchronously with the switching device in the main exchange until position *11* is reached. Then it is moved on as far as position 20 *17* alone by means of impulses from the main station, whereupon it completes the final step into the normal position together with the switching device of the main exchange. During the release motion of the switching devices seizing 25 cannot take place again until the two switching devices have returned to the normal position, since, in the case of an incoming call, relay *Y30* which takes up the initiation of a call is otherwise not energized.

30

Internal calls

Seizing the connecting line leading to the main exchange by the calling subscriber attached to the subsidiary exchange takes place in the same 35 way as has already been described in the case of outgoing traffic. While in the case of outgoing traffic (exchange calls) the subscriber had to dial the characterizing digit *1*, in the case of internal calls he must now dial the number 40 which the desired subscriber has for internal calls, immediately. Since the digit *1* is employed for outgoing traffic, the internal numbers of the subscribers are limited to the numbers 2 to 10. Thus in this case 9 subscribers can be 45 attached to the subsidiary exchange.

As described above, relays *J30* and *V30* are energized during the calling, while relay *P30* is intermittently deenergized by the impulses, so that if, for example, the calling subscriber *A2* desires 50 a connection to subscriber *A3* and accordingly dials the digit *3*, magnet *W32* receives three impulses over the lead *b2* and contacts *374p30* and *375p30* (impulse contact). The auxiliary selector *LW30* is thus set on the third contact. 55 The characterizing switching device is advanced synchronously by its magnet *D30* to the third contact. After the dialling relay *V30* is deenergized and relay *Z30* is influenced over: earth, battery, relay *Z30*, contact *366v30*, wiper *di I 30* 60 in position *3*, earth. Since the impulse contact *354p30* in the main exchange loop is shunted during the dialling, by contact *355/30*, the connecting devices of the main exchange are not set. By the opening of contact *356/30* the pre-selecting 65 device in the main exchange is now no longer seized. Since relay *J30* remains energized over: earth, contacts *320y30*, *322j30*, *321p31*, wiper *di III 30*, relay *J30*, battery, earth, relay *R30* is operated over: earth, battery, relay *R30* contacts 70 *369j30*, *370e30*, 3 seconds switch. Subscriber *A3* is called by ringing current transmitted from the main exchange: ringing current source, contacts *350p30*, *332z30*, *333p30*, lead *a2* of the connecting line, winding *I* of relay *U32*, wiper *a2* of the auxiliary selector *LW30* in position *3*, subscriber *A3*, 75

wiper *b2* of the auxiliary selector *LW30* in position *3*, winding *II* of relay *U32*, contact *303u32*, earth. Since relay *R30* is influenced over a second switch ringing current is transmitted to the desired subscriber every three seconds. The calling subscriber receives part of this ringing current as a "free" signal over contact *310r30*.

If the desired subscriber replies within a pause in the ringing i. e. at a moment when relay *R30* is deenergized the following circuit is set up: 10 earth, contact *503u32*, winding *II* of relay *U32*, wiper *b2* of the auxiliary selector *LW30* in position *3*, subscriber *A3*, wiper *a2* of the auxiliary selector *LW30* in position *3*, winding *I* of relay *U32*, lead *a2* of the connecting line, contacts 15 *333p30*, *332z30*, *331r30*, winding *I* of relay *P31*, battery, earth. In this circuit relays *P31* and *U32*, energize. Since contact *303u32* is opened on the energizing of relay *U32*, the earth necessary for holding relays *U32* and *P32* energized is 20 connected through contact *311p31* and winding *II* of relay *P31*, after the lead *b2* of the connecting line has been switched through. Meanwhile relay *J30* is deenergized by the opening of contact *321p31* and relay *R30* is deenergized by the 25 opening of contact *369j30*, so that further transmission of ringing current is prevented. The feeding current for both subscribers is supplied from the main exchange. For subscriber *A2* the circuit runs from the battery connected to lead 30 *a1* and relay *P30*, to the earth connected through the choke coil *Dr31* to lead *b1*, while for subscriber *A3* current is fed from the battery connected through winding *I* of relay *P31* to lead *a2* of the connecting line, to the earth connected 35 through winding *II* of relay *P31* to lead *b2*.

Metering of internal calls takes place by the meter *SM2* of the calling subscriber *A2*, connected through the switching device of the main exchange (wiper *d II 30*), being influenced over 40 contacts *362z30*, *323z30*, *320y30*, and earth.

On the termination of the conversation, when the calling subscriber replaces his receiver relays *P30* and *U31* deenergize. Contact *319p30* opens and relay *Y30* is thus deenergized, while by 45 the opening of contact *333p30* relay *P31* is deenergized. By the closing of contact *342y30* battery is connected to the *b1* lead of the connecting line over relay *K30*, so that the magnet *W31* of selector *DB30* in the subsidiary exchange is 50 energized. By the alternate play which has already been described above, the selector of the subsidiary exchange is advanced synchronously with the switching devices of the main exchange so that both switching devices are stepped round 55 as far as position *11*. In position *11* relay *H30* again energizes and causes the auxiliary selector *LW30* in the subsidiary exchange to be advanced in the manner already described, under the influence of the corresponding magnet *W32*. The characterizing switching device is switched on together with this selector. When these two switching devices reach the normal position by the switching operations described above, the selector *DB30* of the subsidiary exchange is 60 moved on automatically under the control of relays *K30* and *Y30* in the main exchange until it reaches position *17*. It then completes the final switching step into the normal position together with the switching device in the main 65 exchange.

This short description of the release motion should suffice, since a detailed description has already been given of the release in the case of an outgoing call.

If the called subscriber of an internal call does not reply, relay P30 releases when the calling subscriber replaces his receiver, while relay J30 is only released after the release of relay Y30.

- 5 Accordingly the earth is disconnected from the metering circuit by contact 320y30 before contact 323j30 closes so that in this case metering does not take place.

Special circuits

10 If the selector DB30 in the subsidiary exchange is displaced from the normal position by hand, earth is connected over contact 301w31 to lead a² over wiper a² of the auxiliary selector LW30, so that relay X30 is energized in the main exchange and locks up over contact 373x30. Battery is connected to the b¹ lead over contact 331x30 and thus the magnet W31 in the subsidiary exchange is influenced in series with relay K30 in the main exchange. The selector DB30 is now held until magnet D30 in the main exchange has been switched on through the closing of contact 316k30 whereupon both switching devices are advanced synchronously as in the case 15 of a subscriber's call, until they reach position 11. In this position relay E30 energizes, as in the case above, and causes the auxiliary selector LW30 in the subsidiary exchange and the characterizing selector (rotary magnet Di) to advance synchronously to position 11, whereupon the auxiliary selector continues to advance alone into position 17 in precisely the same way as in the case of the release of an outgoing call, the last step into the normal position being executed 20 together with the characterizing switching device. After this selector DB30 is advanced into position 17 and then finally into the normal position the last step being made together with the switching device of the main exchange. If the magnet W32 of the auxiliary selector is displaced from the normal position by hand contact 305w32 (1017) connects earth over wiper a¹ of the selector DB30 to the a¹ lead of the connecting line, so that relay X30 is again influenced. In a manner corresponding to that above, selector DB30 and the switching device in the main exchange which is operated by magnet D30, are again advanced, whereupon after reaching position 25 11, the magnet W32 of auxiliary selector LW30 is influenced synchronously with the characterizing switching device Di30. The release motion thus takes the same course as is described above. If both selectors in the subsidiary exchange are displaced from the normal position simultaneously, then since contacts 0 and 1 are connected together in the auxiliary selector, earth is connected to the lead a² of the connecting line over contact 301w31, so that again 30 relay X30 is operated and the release motion described above takes place.

If the switching device in the main exchange which is operated by magnet D30 is displaced from the normal position by hand, battery is connected to lead b¹ over wiper d IV 39, and hence the selector DB30 in the subsidiary exchange and the switching device in the main exchange are advanced by the known interaction. All other operations take place as above. In contrast with the movements described above, the connecting line cannot be seized during this return motion, because relay X30, which prepares a circuit for the testing relay P30, is not energized. If the characterizing switching device which is operated by magnet Di30 is displaced by hand 35

from the normal position, relay E30 energizes over wiper d IV 30, and through contact 338e30 completes a circuit for magnet W32 in the subsidiary exchange and relay K30 in the main exchange, so that now the characterizing switching device in the main exchange and the auxiliary selector LW30 in the subsidiary exchange are advanced synchronously by the interaction as above. If, for example, at this moment seizing 5 takes place on the part of the final selector, in the main exchange, relays An30 and C30 can be energized but the selector DB30 in the subsidiary exchange can only be set when the characterizing selector Di30 is in the normal position, so that relay Z30 releases and by closing contact 339c30 10 connects battery to the b¹ lead of the connecting line. Each seizure is indicated by the lighting up of the seizing lamp L. Seizing can also be recorded. If seizing in the incoming and outgoing directions is to be recorded separately the 15 contacts 372h30 and 37an30 can be led separately to a recording device.

What is claimed is:

1. In an automatic telephone system, a main and a subsidiary exchange, a trunk line connecting said exchanges together, means controlled by a calling subscriber in the subsidiary exchange for establishing a connection over said trunk line with a subscriber in the main exchange, a meter at the main exchange individual to said calling subscriber, means for operating said meter responsive to the calling subscriber replacing his receiver to terminate the established connection, a relay at the main exchange, and means controlled by said relay for maintaining said connection established during the operation of said meter.

2. In an automatic telephone system, a main and a subsidiary exchange, a trunk line extending between said exchanges, means for establishing a connection from a subscriber in the subsidiary exchange over said trunk line to a subscriber in the main exchange, a meter at the main exchange associated with the calling subscriber, a relay at the main exchange associated with said trunk line and operated to maintain the established connection between the subscribers, means for operating the calling subscriber's meter when the established connection is to be released, said relay remaining operated to maintain said connection over said trunk line during the time said meter is being operated.

3. In an automatic telephone system, a main and a subsidiary exchange, a trunk line extending between said exchanges, means controlled by a calling subscriber for establishing a connection over said trunk line with a called subscriber in the main exchange, a meter at the main exchange individual to the calling subscriber, a relay at the main exchange associated with said trunk line, said relay controlled by said calling subscriber and operated to maintain the established connection over said trunk line, means responsive to the replacement of the receiver by the calling subscriber for operating said meter and for maintaining said relay operated to hold the connection over the trunk line until said metering operation has been completed although the calling subscriber has replaced his receiver.

4. In a system according to claim 3 wherein the relay is operated under control of the calling subscriber upon the initiation of a call, and held operated for the duration of the call under control of the calling subscriber and in the circuit of

the meter, while when the calling subscriber disconnects the relay is held energized in the meter operating circuit alone.

5. In an automatic telephone system, a main and a subsidiary exchange, a trunk line extending between said exchanges, means controlled by a calling subscriber for establishing a connection over said trunk line with a called subscriber in the main exchange, a meter at the main exchange 10 individual to the calling subscriber, a relay at the main exchange associated with said trunk line, said relay controlled by said calling subscriber and operated to maintain the established connection over said trunk line, means responsive 15 to the disconnection of the calling subscriber for operating said meter and for maintaining said relay operated to hold the connection over the trunk line until said metering operation has been completed although the calling subscriber has 20 disconnected, said relay being connected in series with said meter and maintained energized for the duration of the call by current means to which said meter is non-responsive.

6. In an automatic telephone system, a main and a subsidiary exchange, a trunk line connecting said exchanges, a selector switch in said trunk line at the subsidiary exchange, a relay at the main exchange associated with said trunk line, said relay operated responsive to the initiation 25 of a call from a subsidiary exchange subscriber to a main exchange subscriber, means controlled by said relay for operating said selector switch to establish the connection with the calling subscriber, a meter for the calling subscriber at the main exchange, said meter operated 30 responsive to the disconnection of the calling subscriber, and means for holding said relay operated until said metering operation is completed, said relay maintaining the connection 35 over said trunk line and said selector switch operated during said metering operation.

7. In a system according to claim 6 wherein the relay is responsive to the initiation of the call to transmit impulses to the selector switch at 40 the subsidiary exchange to operate the same to establish the connection and also serves as a testing relay for said selector to test for the calling line.

8. In an automatic telephone system, a main and a subsidiary exchange, a trunk line extending between said exchanges, means controlled by a calling subscriber in the subsidiary exchange for establishing a connection over said trunk line between the exchanges to another subscriber 50 in the subsidiary exchange, switching mechanism at said main exchange associated with said trunk line and operated to control the setting up of the connection, a meter at the main exchange for each of said subsidiary subscribers, the 55 meter of said calling subscriber selected and connected up by said switching mechanism, and means for operating the selected calling subscriber's meter.

9. In a system according to claim 8 wherein the switching mechanism controlling the selecting and connecting up of the meter of the calling subsidiary subscriber also is operated to determine whether the call is to be extended to another local subsidiary subscriber or to a main 60 exchange subscriber.

10. In an automatic telephone system, a main and a subsidiary exchange, a trunk line extending between said exchanges, means controlled by a calling subscriber in the subsidiary exchange 65 for establishing a connection over said trunk

line between the exchanges to another subscriber in the subsidiary exchange, switching mechanism at said main exchange associated with said trunk line and operated to control the setting up of the connection, a meter at the 5 main exchange for each of said subsidiary subscribers, the meter of said calling subscriber selected and connected up by said switching mechanism, and means for operating the selected calling subscriber's meter, said switching mechanism comprising a selector switch operable to determine whether the call is to be extended to another local subsidiary subscriber or to a main exchange subscriber, said meter operating means comprising a relay operated only by said switching mechanism in the position it assumes when it determines that a call is to be extended from one subsidiary subscriber to another subsidiary subscriber. 10 15

11. In an automatic telephone system, a main and a subsidiary exchange, a trunk line extending between said exchanges, means controlled by a calling subscriber in the subsidiary exchange for establishing a connection over said trunk line between the exchanges to another subscriber in the subsidiary exchange, switching mechanism at said main exchange associated with said trunk line and operated to control the setting up of the connection, a meter at the main exchange for each of said subsidiary subscribers, the meter of 20 25 said calling subscriber selected and connected up by said switching mechanism, means for operating the selected calling subscriber's meter, and a relay at the main exchange operated responsive to the answering of the called 30 35 subsidiary subscriber for operating the calling subsidiary subscriber's meter.

12. In a measured service telephone system, a main exchange, a sub-exchange, a trunk line connecting said exchanges, a finder switch in the 40 sub-exchange, sub-exchange subscribers' lines terminating in the banks of said finder switch in the sub-exchange, means responsive to the initiation of a call by one of said subscribers' lines for operating said finder switch to connect 45 said trunk line to the calling line, an auxiliary switch individual to said trunk line in the main exchange, a meter individual to each said sub-exchange subscriber's line terminating in the banks of said auxiliary switch, and means for 50 operating said auxiliary switch in synchronism with said finder switch to select the meter individual to the calling subscriber's line.

13. In a measured service telephone system, a main exchange, a sub-exchange, a trunk line 55 connecting said exchanges, a finder switch in the sub-exchange, sub-exchange subscribers' lines terminating in the banks of said finder switch in the sub-exchange, means responsive to the initiation of a call by one of said subscribers' lines for operating said finder switch to connect 60 said trunk line to the calling line, an auxiliary switch individual to said trunk line in the main exchange, a meter individual to each said sub-exchange subscriber's line terminating in the banks of said auxiliary switch, means for operating said auxiliary switch in synchronism with said finder switch to select the meter individual to the calling subscriber's line, means for completing the connection over said trunk line to a 65 70 called subscriber's line, and means for thereafter operating the selected meter individual to said calling subscriber to charge for the completed connection.
